(57) **CLAIM**

The ornamental design for a charging station, as shown and described.

DESCRIPTION

FIG. 1 is a perspective view of a charging station showing our new design;

FIG. 2 is a top view of a charging station of FIG. 1;

FIG. 3 is a bottom view of a charging station of FIG. 1;

FIG. 4 is a left side view of a charging station of FIG. 1;

FIG. 5 is a right side view of a charging station of FIG. 1;

FIG. 6 is a front view of a charging station of FIG. 1; and,

FIG. 7 is a rear view of a charging station of FIG. 1.

The broken lines in the figures represent portions of the article which form no part of the claimed design.

1 Claim, 6 Drawing Sheets

FIG. 2

FIG. 3

FIG. 4

FIG. 5

FIG. 6

FIG. 7
